CIRCUIT INTERRUPTER OF THE SINGLE-BUSHING TYPE WITH CANTED TERMINAL-BUSHING CONSTRUCTION

Robert E. Friedrich, Baldwin, Carl G. Lentjes, Churchill, and George B. Cushing, Penn Hills, Pa., assignors to Westinghouse Electric Corporation, East Pittsburgh, Pa., a corporation of Pennsylvania

Filed Sept. 15, 1959, Ser. No. 840,133

7 Claims. (Cl. 200—148)

This invention relates to circuit interrupters in general, and, more particularly, to improved mounting constructions and arc-extinguishing arrangements therefor.

As well known by those skilled in the art, in the tank-type oil circuit interrupter a grounded tank is employed with two terminal bushings extending thereinto and supporting at the lower ends thereof arc-extinguishing units bridged by the usual bridging bar. It is, of course, obvious that the terminal bushings, of which there are two for each pole-unit, constitute expensive items of electrical equipment, and it would be of advantage, both as regards space and cost, to eliminate one of the two terminal bushings. The use of terminal bushings, however, extending into a grounded tank, or casing, permits the utilization of inexpensive through-type current transformers. Such through-type, or ring-type current transformers may merely encircle the terminal bushing adjacent the central grounded portion thereof and are, as well known, considerably less expensive than wound-type current transformers, which must be wound with adequate insulation to withstand line-to-ground voltage.

The present invention relates to interrupting apparatus in which only a single terminal bushing is employed, as contrasted to the use of two terminal bushings for tank-type circuit interrupters. Thus, the inexpensive ring-type current transformer may be utilized, and a conventional, stock-item bushing may be used without special construction. Accordingly, the term "circuit-interrupter of the single-bushing type" means herein a circuit interrupter using only a single terminal bushing, which may be of a conventional standard type.

In United States Patent 2,866,045, issued December 23, 1958, to Winthrop M. Leeds, and assigned to the assignee of the instant application, there is disclosed and described a number of single-bushing circuit-interrupting structures. There is a disadvantage to the amount of space taken up by the particular disposition of the circuit interrupting structure of the Leeds device, and it is a general object of the present invention to retain a number of the advantages of the single-terminal-bushing construction of the interrupting device disclosed in the Leeds patent, yet nevertheless rearranging the disposition of the device to result in a considerable saving of horizontal ground space.

A more specific object of the present invention is the provision of a plurality of compact pole units arranged in a space-saving manner, and adapted for simultaneous operation from a single operating mechanism.

A further object of the present invention is the provision of a single-terminal-bushing-type of circuit interrupter, in which preferably the interrupting casing is disposed vertically and contains therewithin the interrupting elements, and the single terminal bushing is disposed in a canted relationship with the upstanding interrupter casing.

A further object of the present invention is the provision of a single-terminal-bushing-type of circuit-interrupting structure in which the disposition of the current transformers around the grounded mechanism housing is such as to register any fault associated with the circuit-

2

interrupting structure as an internal fault, as contrasted with an external fault.

Yet a further object of the present invention is the provision of an improved single-terminal-bushing-type of circuit interrupter in which the several interrupting elements thereof are readily adaptable for removal from the circuit-interrupter housing with a minimum of effort.

Yet another object of the present invention is the provision of an improved circuit-interrupting structure in which the arrangement is such as to facilitate the convection flow of the arc-extinguishing medium to permit its cooling at an upper metallic closure member for the interrupter casing.

Another object of the present invention is the provision of an improved circuit interrupter of the single-terminal-bushing type, in which the operating mechanism is such as to readily adapt the device for multiple-pole operation.

Another object of the invention is the provision of an improved circuit-interrupting structure of the single-terminal-bushing-type, in which use is made of an effective arc-extinguishing gas having a high dielectric strength, such as sulfur hexafluoride (SF₆), whereby the distances between internal parts, at opposite potential, may be a minimum, and the terminal-bushing construction is so configured as to result in a considerable horizontal saving of ground space.

Generally, the present invention is concerned with a single-bushing type of circuit interrupter including a grounded mechanism housing supporting both an outwardly extending interrupting means and also a canted terminal bushing. This results in a space-saving arrangement. In addition, the invention is concerned with a fluid puffer-type interrupter in which a fluid blast is brought about by relative movement between a piston and a cylinder. Such a self-contained interrupter has particular advantages as applied to the foregoing interrupter construction.

To reflect faults associated with the interrupter as internal faults, as contrasted with external faults, a pair of current transformers are mounted upon opposite sides of the grounded mechanism housing and so electrically constructed as to force flashovers to pass to ground between them.

Further objects and advantages will readily become apparent upon reading the following specification, taken in conjunction with the drawings, in which:

FIGURE 1 is an end elevational view of the three-pole circuit-interrupting assemblage with a differential protective relay system incorporated in the drawing to illustrate the functioning of the current-transformer arrangement, the contact structure being diagrammatically indicated in the closed-circuit position;

FIG. 2 is a front elevational view of the three-pole circuit-interrupting assemblage of FIG. 1;

FIGS. 3A, 3B and 3C collectively illustrate an enlarged, vertical sectional view taken through the improved single-bushing-type of circuit interrupter of the present invention, the contact structure being illustrated in the closed-circuit position; and,

FIG. 4 is a fragmentary view, in section, taken along the line IV—IV of FIG. 3A and illustrating the contact structure in the fully open-circuit position.

Referring to the drawings, and more particularly to FIG. 1 thereof, the reference numeral 1 generally designates a single-bushing-type of circuit interrupter supported upon a grounded metallic framework 2. With reference to FIG. 2, it will be noted that three such single-terminal-bushing-types of circuit interrupters may be mounted upon the same grounded frame 2, and a common mechanism compartment 3 may be provided. The mechanism disposed within the mechanism compartment 3 may be of any conventional type, and, when operated, serves

to effect the rotation of a horizontally extending operating rod 4 which interconnects the three pole-units 1.

With reference to FIG. 1, it will be noted that generally each single-terminal-bushing-type of circuit interrupter 1 includes an upstanding insulating interrupter casing 5, a grounded mechanism housing 6, supported by the upstanding framework 2, and a single terminal bushing, generally designated by the reference numeral 7. The terminal bushing 7 may be of a conventional type, such as an oil-filled type, or it may be of the gas-filled type, such as set forth in United States patent application filed December 2, 1959, Serial No. 856,775, by Robert E. Friedrich and James H. Frakes, and assigned to the assignee of the instant application.

Supported upon the mechanism housing 6 and disposed below the interrupter casing 5 is a first current transformer 8, so arranged as to ensure that any faults, or breakdowns occurring along the outer or inner walls of the insulating casing 5 will pass through the first current transformer 8 to ground by way of the framework 2.

A second current transformer 9 is associated with the canted terminal bushing 7 and has the cover plate 10 thereof disposed at such a remote distance from the outer end 11 of the terminal bushing 7, that any breakdown occurring along either the inside or outside surface of the porcelain weatherproof shell 12 will strike to the supporting flange 13 (FIG. 3C) and likewise be carried to ground through the second current transformer 9. As will be more fully brought out hereinafter, it is desired to have any fault condition associated with the circuit-interrupting assemblage 1 sensed as an internal fault condition, as contrasted with an external fault condition. In other words, it is desired to have any fault condition associated with the circuit-interrupting assemblage 1 reflected as an internal fault condition so that the remote circuit interrupters 14, 15 will also open, together with the opening of circuit interrupter 1.

With reference to FIGS. 3B and 3C, it will be noted that the mechanism housing 6, at ground potential, is somewhat of an upwardly extending U configuration. The left leg of the U configuration, indicated by the reference numeral 17 (FIG. 3B), supports the upstanding insulating casing 5, which is preferably formed from porcelain. The right leg 18 of the generally U-shaped mechanism housing 6 supports the terminal bushing 7 by the mounting flange 13 thereof. Crank means, generally designated by the reference numeral 20, includes a rotatable shaft 21, which extends within the interior of the mechanism housing 6 in a gas-tight manner, and is keyed to an internally disposed crank-arm 22, pivotally connected at 23 to a pair of operating rods 24. The operating rods 24 are formed of insulating material, and have lower rod-ends 24a of metallic material.

The rotatable operating shaft 21 may constitute an extension of the rotatable shaft 4 of FIG. 2, which is rotated by the actuation of the mechanism disposed interiorly within the mechanism compartment 3. Thus, clockwise rotation of the operating shaft 21, as viewed in FIG. 3B, effects corresponding clockwise rotative movement of the crank-arm 22, and hence downward opening motion of the pair of insulating operating rods 24. The upper ends of the operating rods 24 have rod-ends 24b (FIG. 4), which are pivotally connected as at 25 to lugs 26, affixed diametrically on opposite sides of a movable metallic puffer operating cylinder 27. At the upper end of the puffer cylinder 27 is an inwardly extending flange portion 27a, to which is bolted, by bolts 28, a movable contact support 29. The movable contact support 29 is, in turn, bolted by bolts 30, FIG. 3A, to a movable contact, generally designated by the reference numeral 31. The movable contact 31 includes a plurality of circumferentially spaced flexible spring fingers 32, and a bayonet-type arcing contact 33. The movable fingers 32 and the arcing contact 33 make contacting engagement with a downwardly extending, rod-shaped relatively stationary con-

tact 34. The lower tip portion of the rod-shaped stationary contact 34 is hollowed, as at 34a, to accommodate the upper extremity of the arcing contact 33, as shown in FIG. 3A.

5 The upper end of the relatively stationary contact 34 is adjustably threadedly secured within a clamp 35, which is bolted as at 36, to an annular mounting plate 37. The mounting plate 37 is secured, by bolts 38, to a mounting flange ring 39, cemented to the upper end of the casing 5. In addition, an upper closure inspection plate 40 is provided, being bolted by bolts 41 to the annular mounting plate 37.

Movable contact support 29 has an upper extension 42, to which is bolted by bolts, not shown, an insulating orifice member 43. The movable contact support 29 also has apertures 44 (FIG. 4) provided therethrough, through which an upward moving blast of gas passes from a compression chamber, generally designated by the reference numeral 45.

15 20 The compression chamber 45 is provided by the coaction between the puffer cylinder 27 and a fixed piston 46. It will be obvious, therefore, that relative motion between the operating cylinder 27 and the fixed piston 46 will result in a raising of the pressure within the compression chamber 45 and an ejection of compressed fluid upwardly 25 from the chamber 45, through the apertures 44, and through the orifice opening 47 of the orifice sleeve 43 to effect extinction of the arc 19 (FIG. 4) drawn therethrough.

30 Although FIG. 4 illustrates the fully open circuit position of the interrupter 1, nevertheless, for purposes of illustration, the drawn arc 19 has been drawn into the figure, together with arrows 16 indicating the gas blast. Arc extinction quickly follows.

35 35 The fixed piston 46 constitutes the upper extremity of an insulating pedestal, generally designated by the reference numeral 48, which is mounted, as at 49 (FIG. 3B), to a lower plate portion 50 of the mechanism housing 6. A removable cover 51 is bolted, by bolts 52, to the same 40 plate portion 50, and permits downward withdrawal of the insulating pedestal 48 for maintenance and service operations, as more fully brought out hereinafter.

45 45 Adjacent the lower end of the insulating cylindrical pedestal 48 is a cutout portion 53 which accommodates a tubular conductor 54, having an elbow connection, as at 55, to a horizontally extending tubular conductor 56, which is attached to the lower end 57 of the terminal bushing 7.

50 50 Secured, as by a press fit, to the upper end of the tubular conductor 54 is a contact support 58, having integrally formed flexible stationary fingers 59. Contacting, in sliding engagement, with the stationary fingers 59 is a downwardly extending rod-shaped portion 60 of the movable contact structure 31. As shown in FIG. 3A, the contact support 58 is secured, as by stud bolts 61, to the fixed piston 46, the latter constituting an upper closure plate for the tubular pedestal support 48. In addition, one-way acting valves 62 are provided, being spring-biased to their open position, as shown, to permit the ready 55 60 passage of fluid upwardly from the region 63 (FIG. 3A) interiorly of the pedestal support 48 and into the compression region 45 in the closed-circuit position of the interrupter. However, upon downward opening movement of the operating cylinder 27, the several valves 62 65 will, of course, close by virtue of the gas pressure present within region 45.

65 70 In the closed-circuit position of the interrupter 1, the electrical circuit therethrough includes upper line terminal 64, relatively stationary contact 34, movable contact 31, lower extension 69 of movable contact 31, fingers 59, tubular conductor 54, horizontal conductor 56, and the terminal stud, not shown, extending axially through the terminal bushing 7 to the outer terminal extremity 65 thereof.

75 To effect the opening operation of the interrupter the

mechanism not shown disposed within the mechanism compartment 3 is effective to effect clockwise rotation of the shaft 21 as viewed in FIG. 1. With reference to FIG. 3B, the clockwise rotation of the internally disposed portion of the operating shaft 21 will cause clockwise rotation of the keyed crank-arm 22 to effect thereby downward opening pulling movement of the operating rods 24. Since the upper ends of the insulating rods 24 are secured to the outer sides of the operating puffer cylinder 27, the downward opening movement of the puffer cylinder 27 will compress gas within the region 45, closing the valves 62, and forcing the compressed gas upwardly through the orifice opening 47 to effect extinction of the arc 19 drawn therethrough, as shown in FIG. 4.

The first downward opening movement of the movable contact structure 31 will effect separation between the relatively movable fingers 32 and the external side 34b of the rod-shaped stationary contact 34. The arcing contact 33 will subsequently separate from the relatively stationary contact 34, so that no burning occurs upon the finger contacts 32. The arc 19 will, therefore, extend between the upper tip extremity of the arcing electrode 33 and the annular arc resisting portion 34c of the stationary rod contact 34. Since the gas enclosed within the casing 5 is preferably a highly efficient arc-extinguishing gas having a relatively high dielectric strength, such as sulfur hexafluoride (SF₆), the extinguishing action exerted upon the arc 19 will take place very quickly, and the arc 19 will become extinguished.

With reference to FIG. 1, it will be observed that a remote circuit interrupter 14 is connected by a transmission line 65 to the circuit interrupter 1. The remote circuit interrupter 14 includes a pair of stationary contacts 66 bridged by a movable contact 67, biased by gravity to an open position, and retained in the closed position by a latch 68, released by the energization of a solenoid 69 and associated armature 70. A current transformer 71 measures the current through the circuit interrupter 14 from the line connection L₁. The secondary winding of the current transformer 71 is connected in parallel with the secondary winding of the current transformer 9 and also with the winding 72 of a differential protective relay, generally designated by the reference numeral 73. When the differential relay 73 becomes energized and bridges its stationary contacts 74 by the upward movement of a movable bridging contact 75, a tripping circuit is established from the source 76 to effect opening of the circuit interrupter 14, and also energization of winding 77 tripping the circuit interrupter 1 open. More specifically, the rotatable shaft 4 is diagrammatically represented in FIG. 1 as being biased by a compression spring 78 to an open-circuit position, and latched in the closed-circuit position by a latching device 79, which is pivotally connected to a pair of armatures 80, 81.

The winding through the differential relay 73 is responsive to the difference of current through the line L₁ and the current passing through the circuit interrupter 1, as well known by those skilled in the art. Similarly, a differential protective relay 82, having a winding 83, is also responsive to the difference of the current passing through the line L₂ and the current carried by the circuit interrupter 1. Reference may be had to United States patent application, filed March 31, 1958, Serial No. 725,286, now U.S. Patent 3,032,689, issued May 1, 1962, to Benjamin P. Baker and Robert F. Karlicek, and assigned to the assignee of the instant application, for the general theory and operation of the differential protective relays 73, 82.

It will be noted that any fault current flashing over the inside or outside surface of the porcelain casing 5, as indicated by the flashover conditions 95, 96 in FIGS. 1, 3A and 3B, will flow to ground through the first current transformer 8. Thus, assuming that the current is flowing in the direction of the line L₁ toward the circuit inter-

rupter 1, the current transformer 71 will register the fault current, whereas the second current transformer 9, associated with the circuit interrupter 1, will register zero current. Such a condition will cause the operation of the differential relay 73 to complete the tripping circuit 98 to effect opening of the circuit interrupters 1 and 14.

Similarly the current transformer 8 will measure full fault-produced current, whereas current transformer 85, associated with remote circuit interrupter 15, will register zero fault-produced current. As a result, differential relay 82 will be actuated to trip circuit breakers 1 and 15. Hence all three breakers 1, 14 and 15 open under such an internal fault-condition represented by flashover 95 or 96.

Likewise, should the current be considered as flowing from the line L₂, through the remote circuit interrupter 15 and toward the circuit interrupter 1, the current transformer winding 85 will measure the fault current, whereas the current transformer 8 will register zero current since the fault current reverses its direction through the current transformer 8. As a consequence, differential relay 82 will pick up its contacts 86 by the bridging member 87, and complete the tripping circuit 88 to trip the circuit interrupter 15 open as well as the circuit interrupter 1. In addition, current transformer 9 will register the fault current, whereas current transformer 71 will register zero current. Consequently, differential relay 73 will pick up and open circuit interrupters 1 and 14. As a result, such an internal fault condition 95 or 96 will be sensed as an internal fault condition and will effect tripping of both circuit interrupters 14 and 15 as well as the circuit interrupter 1.

In a similar manner, a breakdown, as at 90, (FIGS. 1 and 3C) over the external surface of the porcelain casing 12 of the terminal bushing 7 will pass to ground through the second current transformer 9, and, by operation of the differential protective relays 73, 82, will insure that breakers 14 and 15 open as well as circuit interrupter 1.

From the foregoing description, it will be apparent that the particular disposition of the first and second current transformers 8, 9, associated with the circuit interrupting assemblage 1, is such that any breakdown, or fault condition associated with the circuit interrupter 1 will pass to ground through the current transformers 8, 9 and be sensed as an internal fault condition causing circuit interrupter 1 as well as remote breakers 14, 15 to open. To insure that the fault current passes to ground through the current transformer 8, the latter has an outer, insulating peripheral cover 8a, to insure that if the fault strikes the upper side of the current transformer 8, it will pass to ground through the current transformer 8, and not externally thereof.

From the foregoing description of the invention, it will be apparent that there is provided an improved circuit-interrupting structure of the single-terminal-bushing type, in which considerable ground space is saved by the canted arrangement of the terminal bushing 7. The circuit interrupter of the present invention is intended for use in the medium voltage range, and for high continuous current ratings. A substantial short-circuit interrupting capacity, say of the order of 3500 mva., is anticipated.

It will be noted that the three poles 1 of the circuit interrupter are mounted side by side on the grounded structural steel frame 2, that elevates live parts safely above the ground. The pole units 1 are simultaneously operated by a single mechanism disposed within the mechanism compartment 3, which may be of conventional design. Since this mechanism compartment 3 is situated within the supporting framework 2, the overall length and width are held to the minimum necessary to support the pole units.

Each pole unit 1 is comprised of a vertical porcelain column 5 housing the interrupter structure, and a single, canted bushing 7 of standard external dimensions, and of

conventional condenser-type design. It will be noted that the terminals 64, 65 for the circuit interrupter 1 are provided at the top of the bushing 7 and at the top of the interrupter column 5. All are located in the same horizontal plane at an elevation safely above the work area. The folded configuration of each pole unit 1 avoids an unnecessarily wide, space-wasting span between the terminals 64, 65. Also the adjacent pole units 1 may be spaced as closely as electrical clearances permit, giving a compact overall arrangement.

It will be noted that there is space available for two current transformers in each location, resulting in a total of four current transformers possible per pole unit 1.

It will be noted that the stationary contact 34 is mounted beneath the dome 40, which forms the top of the vertical interrupter column 5. Below it, in this column, is the moving contact structure 31, which comprises an orifice, finger-type main contacts, a bayonet-type arcing contact and a puffer cylinder 27, supported on a pedestal 48 mounted in the pole-unit base. The moving contact structure 31 is actuated through insulating pull rods 24, connected to lugs 26 on the sides of the puffer cylinder 27 and at the lower ends to two cranks 22 actuated by the circuit-breaker mechanism.

As the breaker opens, downward movement of the pull-rods 24 separate, successively, the main contacts and the arcing contacts, and then draws an arc 19 within the interrupting orifice 43. Gas, compressed within the cylinder 27 during the opening stroke, is forced through the orifice 43 in a puff to extinguish the arc 19. Current is collected from the lower end of the moving contact structure 31 through stationary finger contacts 59, which are, in turn, connected by a tubular conductor 54 to the lower end of the bushing 7.

It is intended, for certain applications, that this pole-unit 1 be charged with sulfur hexafluoride (SF_6) gas, or a similar gas of proven arc-interrupting ability. The unit 1 is essentially gas-tight in construction. Consequently the initial charge of gas should suffice until maintenance is required after several years of service. The sulfur-hexafluoride gas provides dielectric strength between live parts and ground within the structure, and also serves as the arc-interrupting medium. The drive shaft 4 is sealed at the point where it enters the pressure-type housing 6 with either a conventional O-ring type of seal, or a clamped tubular type seal, such as disclosed in United States Patent 2,889,434, issued June 2, 1959, to Harry J. Lingal and assigned to the assignee of the instant application.

It will be noted that the contact components are readily accessible for servicing and inspection after the gas has been bled out of the pole-unit 1. Removal of the dome-shaped cover 40 at the top of the vertical column 5 permits the stationary contact 34 to be extracted. Following this, the moving contacts may either be inspected in place, or taken out by removing the bolts 28 that attach the assembly to the puffer cylinder 27. This assembly also includes the sliding contact 60 which connects with the tubular conductor 54 leading to the terminal bushing 7.

The complete movable contact structure 31 that is supported upon the pedestal 48, excluding the stationary contact 34 supported in the dome 40, may be removed from beneath the pole-unit housing 6. This is a desirable feature because the worker is located close to ground for his own safety, and the amount of rigging equipment is minimized. The horizontal conductor 56 must be disconnected at the elbow 55 at the contact supporting post 48. Also, the contact operating pull rods 24 must be disconnected from the driving cranks 22. For these operations, access is provided through the bottom of the interrupter at the base of the pedestal 48 by removing the cover plate 51 on the bottom of the housing 6. This also provides access to the pedestal mounting flange 49. Removal of bolts 49a in it permits the pedestal 48 and

5 moving contact components 31 to be lowered out of the bottom of the pole-units 1.

The vertical orientation of the interrupter column 5 affords advantages in heat dissipation. Resistance losses cause the conducting parts to heat, and the gas surrounding these parts is, in turn, also heated. However, the tubular construction of the orifice 43, the cylinder 27, and the supporting pedestal 48 forms a chimney, which carries these hot gases upwardly, by convection, to the dome 40 at the top of the column 5. The dome 40, being metallic, conducts the heat from these gases outwardly to the surrounding ambient air. In necessary, this feature can be further enhanced by providing a larger dome 40 and equipping it with integral fins.

It is to be observed that check valves 62 have been provided at the bottom of the puffer cylinder 27. In addition to permitting the passage of gas for the cooling effect described, these valves 62 also permit the cylinder 27 to breathe in gas during the closing stroke, which has not been contaminated, or heated by arcing.

The particular circuit-interrupting structure 1, disclosed herein, has the following advantages:

(1) It provides a gas-type of circuit interrupter providing two current transformers or more if required per terminal.

(2) A gas-type circuit interrupter results having current transformers located to provide overlapping differential relay protection.

(3) A gas-type circuit interrupter providing the simplicity of a sealed, self-contained unit.

(4) A gas-type circuit interrupter arranged in a vertical column to enhance heat dissipating ability to provide high continuous current ratings.

(5) A gas-type circuit interrupter having the mechanism located for minimum overall breaker dimensions.

(6) The invention provides a gas-type circuit interrupter designed for ease of inspection and maintenance.

(7) A gas-type of circuit interrupter is obtained having live parts equidistant above ground at the requisite elevation for safety.

(8) The circuit interrupter has pole units 1 of folded configuration to thereby minimize space requirements.

(9) A circuit-interrupting structure results which is simple in construction for economical manufacture.

Although there has been illustrated and described a specific circuit-interrupting structure, it is to be clearly understood that the same was merely for the purpose of illustration, and that changes and modifications may readily be made therein by those skilled in the art without departing from the spirit and scope of the invention.

We claim as our invention:

1. A circuit interrupter of the single-bushing type including an upstanding insulating cylindrical interrupter housing, a relatively stationary contact disposed interiorly within the upper end of said cylindrical interrupter housing, a longitudinally movable puffer cylinder carrying a movable contact disposed interiorly within said cylindrical interrupter housing, the movable contact being co-operable with the relatively stationary contact to establish an arc, the movement of the puffer cylinder forcing fluid under pressure toward the established arc to effect the extinction thereof, a grounded mechanism housing disposed below said upstanding cylindrical interrupter housing and serving to support the same, a canted terminal bushing of conventional type supported by said grounded mechanism housing, the angle between the axial center lines of the interrupter housing and the terminal bushing being less than 180°, and a removable cover plate secured to the bottom of the mechanism housing to effect downward withdrawal of the movable puffer cylinder for service and maintenance.

2. The combination in a single-bushing type of circuit interrupter of an upstanding hollow insulating interrupter casing, a grounded support housing disposed below said hollow insulating interrupter casing and serving to support

the same, interrupting elements disposed within said hollow casing for establishing and extinguishing an arc, a canted terminal bushing supported by said grounded support housing, a pair of current transformers, one of said current transformers being disposed below the hollow casing so that any fault to ground over the casing will pass to ground through said one current transformer and the sensed as an internal fault, the other current transformer being mounted upon said grounded support housing in such relation to the protruding end of the terminal bushing that any breakdown over the external end of the terminal bushing will be sensed as an internal fault.

3. The combination in a single-bushing type of circuit interrupter of an upstanding hollow insulating interrupter casing, a grounded support housing disposed below said hollow insulating interrupter casing and serving to support the same, a relatively stationary contact disposed within the upper end of the hollow casing, a movable contact cooperable with the relatively stationary contact to establish an arc, a movable puffer cylinder carrying said movable contact and operable to force a blast of fluid under pressure at the established arc to effect the extinction thereof, a canted terminal bushing supported by said grounded support housing, a pair of current transformers, one of said current transformers being disposed below the hollow casing so that any fault to ground over the casing will pass to ground through said one current transformer and be sensed as an internal fault, the other current transformer being mounted upon said grounded support housing in such relation to the protruding end of the terminal bushing that any breakdown over the external end of the terminal bushing will be sensed as an internal fault.

4. A circuit interrupter of the single-bushing type including an upstanding insulating cylindrical interrupter housing, a relatively stationary contact disposed interiorly within the upper end of said cylindrical interrupter housing, a longitudinally movable puffer cylinder carrying a movable contact disposed interiorly within said cylindrical interrupter housing, the movable contact being cooperable with the relatively stationary contact to establish an arc, the movement of the puffer cylinder forcing fluid under pressure toward the established arc to effect the extinction thereof, a grounded mechanism housing disposed below said upstanding cylindrical interrupter housing and serving to support the same, a canted terminal bushing of conventional type supported by said grounded mechanism housing, and the angle between the axial center lines of the interrupter housing and the terminal bushing being less than 180°, crank means disposed within said mechanism housing, and longitudinally extending operating-rod means interconnecting said crank means and said longitudinally movable puffer cylinder, and a removable cover plate secured to the bottom of the mechanism housing to effect downward withdrawal of the movable puffer cylinder for service and maintenance.

5. A circuit interrupter of the single-bushing type including an insulating cylindrical interrupter housing, a relatively stationary contact disposed interiorly within the upper end of said cylindrical interrupter housing, a longitudinally movable puffer cylinder carrying a movable contact disposed interiorly within said cylindrical interrupter housing, the movable contact being cooperable with the relatively stationary contact to establish an arc, the movement of the puffer cylinder forcing fluid under pressure toward the established arc to effect the extinc-

tion thereof, a grounded mechanism housing disposed below said cylindrical interrupter housing and serving to support the same, a canted terminal bushing of conventional type supported by said grounded mechanism housing and making an angle with the axial center line of the interrupter housing, and a removable cover plate secured to the bottom of the mechanism housing to effect downward withdrawal of the movable puffer cylinder for service and maintenance.

6. The combination in a single-bushing type of circuit interrupter of a hollow insulating interrupter casing, a grounded support housing disposed below said hollow insulating interrupter casing and serving to support the same, interrupting elements disposed within said hollow casing for establishing and extinguishing an arc, a canted terminal bushing supported by said grounded support housing, a pair of current transformers, one of said current transformers being disposed below the hollow casing so that any fault to ground over the casing will pass to ground through said one current transformer and be sensed as an internal fault, the other current transformer being mounted upon said grounded support housing in such relation to the protruding end of the terminal bushing that any breakdown over the external end of the terminal bushing will be sensed as an internal fault.

7. The combination in a single bushing type of circuit interrupter of a hollow insulating interrupter casing, a grounded support housing disposed below said hollow insulating interrupter casing and serving to support the same, a relatively stationary contact disposed within the upper end of the hollow casing, a movable contact cooperable with the relatively stationary contact to establish an arc, a movable puffer cylinder carrying said movable contact and operable to force a blast of fluid under pressure at the established arc to effect the extinction thereof, a canted terminal bushing supported by said grounded support housing, a pair of current transformers, one of said current transformers being disposed below the hollow casing so that any fault to ground over the casing will pass to ground through said one current transformer and be sensed as an internal fault, the other current transformer being mounted upon said grounded support housing in such relation to the protruding end of the terminal bushing that any breakdown over the external end of the terminal bushing will be sensed as an internal fault.
